SHORT PATH FRACTIONATING CEN- TRIFUGAL STILL

Godfrey Burrows, Sale, England, assignor to
Metropolitan-Vickers Electrical Company Lim-
ited, London, England, a company of Great
Britain

Application December 10, 1948, Serial No. 64,576
In England December 19, 1947

2 Claims. (Cl. 202—205)

1

This invention relates to a short path fractionating still of the centrifugal type which is adapted for operation under vacuum conditions.

A still of this general type is known in which distilland is caused to flow upwards by centrifugal action over a heated evaporating surface of inverted conical form.

The present invention has for an object the provision of an improved form of short path fractionating centrifugal still.

A further object of the invention is to provide a centrifugal still which is particularly adapted for continuous operation with, if desired, varying degrees of reflux of the distillate.

Another object of the invention is to provide a centrifugal still in which provision is made for recirculating residue.

Other objects and advantages of the present invention will become apparent during the course of the following description of the invention with reference to the accompanying drawing, in which:

Fig. 1 is a diagrammatic sectional elevation of a centrifugal still.

Fig. 2 shows a diagrammatic fractional sectional elevation of a modification of the still of Fig. 1.

Essentially the improved still of this invention comprises a plurality of rotatable evaporating bowls arranged in an evacuable housing beneath corresponding condensing surfaces, the arrangement being such that on introducing a distilland into one bowl heavier fractions are eventually transferred to the outermost bowl and into a receiver by centrifugal action, while lighter fractions are transferred inwardly by the condensing surfaces eventually to a central receiver.

Referring to Fig. 1, the still there shown comprises a housing 1 of cylindrical form in plan, in which are arranged four rotatable bowls 2-5 which are separated and arranged for rotation at different speeds. Arranged above the bowls is a condenser 6 which is formed with condensing surfaces 7-10 arranged over the respective bowls 2-5 and shaped so that distillate from one bowl condensing on the surface overhead drips from this surface into the next lower bowl, thus the condensate on surface 10 drips into bowl 4, that from surface 9 into bowl 3, that from surface 8 into bowl 2, whilst the condensate on surface 7 drips into a central stationary receiver 11 arranged on the axis of rotation of the bowls and from which distillate may be withdrawn through the pipe 12 under the control of valve 13. The condenser 6 may be formed as a casting with channels 6' for the circulation of cool-

2

ing liquid and the condensing surfaces 7-10 may be treated as by plating or polishing to facilitate wetting of the surface by the distillate.

Distilland is introduced into the housing 1 of the still through pipe 14 and flows into a receiver 15 from which the overflow passes down the conical surface 16 and through a gap between the condensing surfaces 7 and 8 into bowl 2. Distilland thrown out of the bowl 2 by centrifugal action is deflected by the baffle 17 into the bowl 3, and similarly the distilland thrown out of bowls 3 and 4 is deflected by baffles 18 and 19 into bowls 4 and 5 respectively. The residual distilland thrown out of bowl 5 is deflected by a baffle 20 into an annular trough 21 from which it may be withdrawn through pipe 22.

If desired the residual distilland in the trough 21 may be recirculated through the still. For this purpose a pipe 23 is provided with valve 24 which leads from the trough 21 to a distributor 25 from which liquid flows over conical surface 26 and between gaps in the condensing surfaces 8 and 9 into bowl 3.

The bowls 2-5 are secured to respective concentric sleeves 32-35 which are mounted on a hollow shaft 28 supported in a bearing 29 and are provided with individual gear wheels meshing with gear wheels on the lay shaft 36. It will be appreciated that by choosing the diameters of the respective gear wheels the speeds of the individual bowls may be arranged to suit required operating conditions. Each of the bowls is provided with an individual electric heater 37, the connections to which are made through the slip rings 38 so that one bowl is at a different temperature than that of another bowl.

In the operation of the still, the heavier fractions of the distilland introduced into the bowl 2 will be caused to travel outwards from bowl to bowl by centrifugal action until they reach the trough 21. The lighter fractions however will be caused to travel inwards by the action of the condensing surfaces until they reach the receiver 11. By control of the valve 13 the distillate may be caused to accumulate in the receiver and eventually to spill over into the bowl 2, and in this manner any desired degree of reflux may be obtained.

Also by control of the valve 24 any desired proportion of the residue in the trough 21 may be recirculated through the still. The controls for reflux and recirculation may be varied independently of one another and as required ac-

cording to the kind and proportions of the fractions it is desired to obtain. It will be understood also that the distilland need not be fed to the bowl 2 but could, for example, be introduced into the bowl 3 so as to allow a double fractionation of the distillate. Similarly the residue from the trough 21 may be recirculated to a bowl other than bowl 3 as shown.

In the arrangement shown in Fig. 1, the area of the condensing surface 7 may be too small for some purposes, and a modification providing a larger area is shown in Fig. 2. In this form the central receiver 11' for the distillate is of annular shape and connected with the outlet valve 13 through the channel 39 while the condensing surface 7' is formed as an annulus which extends over the bowl 2 with its inner edge projecting over the outer edge of the receiver 11'.

It will be appreciated that the short path fractionating still of the present invention is particularly suitable for operation under so-called "molecular distillation" conditions, that is under vacuum conditions such that the mean free path of the distilling molecules in their passage from the evaporator to the condenser is of the same order of magnitude or greater than the distance between the evaporator and the condenser, so that the average distilling molecule travels from the evaporator to the condenser substantially without collision with residual gas molecules. The operation of the still is however not necesarily confined to this type of distillation.

What I claim as new and desire to secure by Letters Patent of the United States is:

1. A short path fractionating centrifugal still comprising a plurality of concentric evaporating bowls mounted for rotation about a common axis, means for rotating the bowls at different rates of rotation relative to each other, means for heating the bowls individually, baffles for directing liquid forced by centrifugal action out of one

bowl into the next outer bowl and residue out of the outermost bowl into a stationary annular channel, a plurality of concentric condensing surfaces positioned one over each bowl and shaped to feed condensate back into the next inner bowl, a central stationary receiver for condensate fed from the innermost condensing surface, and means for feeding distilland to one of said bowls.

2. A short path fractionating centrifugal still comprising a plurality of concentric evaporating bowls mounted for rotation about a common axis, means for rotating the bowls at different rates of rotation relative to each other, means for heating the bowls individually, baffles for directing liquid forced by centrifugal action out of one bowl into the next outer bowl and residue out of the outermost bowl into a stationary annular channel, a plurality of concentric condensing surfaces positioned one over each bowl and shaped to feed condensate back into the next inner bowl, a central stationary receiver for condensate fed from the innermost condensing surface, means including a conduit extending from said stationary annular channel to an inner bowl for gravity flow of residue and a valve in said conduit for controllably recirculating residue from said stationary annular channel to said inner bowl, and means for feeding distilland to one of said bowls.
